UNITED STATES PATENT OFFICE.

S. HARRY RUSSELL, OF LEXINGTON, KENTUCKY, ASSIGNOR OF ONE-THIRD TO W. H. YOUNG AND ONE-THIRD TO W. E. LANG, BOTH OF LEXINGTON, KENTUCKY.

OIL SAVER.

Application filed June 26, 1925. Serial No. 39,874.

This invention relates to improvements in apparatus for use in connection with oil well drilling, an object being to provide a device for receiving and saving oil from the tubing of the drilling apparatus when the said tubing is "pulled" from the well.

Another object of the invention is the provision of an oil saving device or receptacle having a novel form of mouth or hopper for directing the oil from the tubing into said receptacle, together with means to prevent the oil from splashing out of the receptacle.

Another object of the invention is the provision of a receptacle having novel supporting means, which means further provides for the return of the salvaged oil into the well, if desired.

With the above and other objects in view, the invention further includes the following novel features and details of construction, to be hereinafter more fully described, illustrated in the accompanying drawings and pointed out in the appended claims.

In the drawings:—

25 Figure 1 is an elevation of the invention shown in position for use.

Figure 2 is a top plan view of the invention per se.

Figure 3 is an end view.

30 Figure 4 is a view looking at the opposite end of the device with the supporting pipe in section.

Figure 5 is a section taken substantially on the line 5—5 of Figure 1.

35 Referring to the drawings in detail wherein like characters of reference denote corresponding parts, the reference character indicates a receptacle which may be of suitable size and shape and which is shown as

40 rectangular. The receptacle is preferably supported at one end by means of a pipe section 11, one end of which is secured within an opening provided in one end wall of the receptacle, while the other end is prefer-

45 ably secured to a casing head 12, the pipe 11 engaging the usual threaded boss 13 provided upon the casing head. The opposite end of the receptacle 10 is supported upon legs 14, the latter being adjustably positioned by means of set screws 15 which ex-

50 tend through a strap or bar 16 secured as at 17 to one end of the receptacle. The legs 14 may thus be independently adjusted so as

55 to properly support the receptacle on ground of any character.

The receptacle is provided with a restricted open top and for this purpose the side walls of the receptacle extend upwardly and inwardly as shown at 17' and upwardly and outwardly as shown at 18, so that a restricted opening 19 is provided from which the walls 17 and 18 extend in opposite directions. The walls 18 are thus outwardly flared and have one of their ends connected to an inclined mouth 20 at one end of the receptacle 10.

Located within the receptacle is an inverted substantially V-shaped baffle which includes oppositely inclined walls 21 whose adjacent edges are connected as shown at 22. The ends of these walls are secured to the opposite walls of the receptacle as shown at 23. The walls 21 are spaced from and arranged substantially parallel with the inclined walls 17' while the lower edges of the walls 21 terminate short of the bottom and side walls of the receptacle.

In the use of the invention, the string of tubing is "pulled" from the well in the usual manner, the sections of the tubing being disconnected at the collar C in the usual well known manner so that the upper section T of the tubing may be swung substantially to the dotted line position illustrated in Figure 1. In this position, the end of the tubing will be over the receptacle so that the oil will flow into said receptacle and will strike the baffle walls 21 to separate the stream and reduce the force of the flow, while the said baffle walls together with the inclined walls 17' will prevent the oil from splashing upward out of the receptacle. The section T of the tubing is supported upon the casing head by the usual elevator E indicated by the dotted lines in Figure 1 of the drawings.

It will be apparent from the foregoing description and accompanying drawings that the invention provides means for salvaging oil ordinarily wasted when pulling the pipe or tubing from a well.

The invention is susceptible of various changes in its form, proportions and minor details of construction and the right is herein reserved to make such changes as properly fall within the scope of the appended claims.

Having described the invention what is claimed is:—

1. An oil saver comprising a receptacle open at the top, means connecting one end of

- the receptacle with the casing head of a well to support said end adjacent the well and means to adjustably support the opposite end of the receptacle.
5. 2. An oil saver comprising a receptacle open at the top, means connecting one end of the receptacle with the casing head of a well to support said end adjacent the well, said connecting means being adapted to deliver 10 the contents of the receptacle to the well and means to adjustably support the opposite end of the receptacle.
3. An oil saver comprising a receptacle having a restricted open top, supporting 15 means for the receptacle, oppositely disposed outwardly flared walls extending along opposite side edges of the receptacle and an outwardly and upwardly inclined
- mouth at one end of the receptacle with the opposite ends of the mouth extending from 20 the adjacent ends of the flared walls.
4. An oil saver comprising a receptacle having a restricted open top, supporting means for the receptacle, upwardly and outwardly flared walls extending from said 25 opening, downwardly and outwardly flared walls extending from the opening, oppositely and downwardly inclined baffle walls located within the receptacle and having their opposite ends secured to the opposite walls 30 of said receptacle, said baffle walls being arranged substantially parallel with and spaced from the downwardly inclined walls and having their adjacent edges connected.

In testimony whereof I affix my signature.
S. HARRY RUSSELL.
